CLAIM

The ornamental design for a cleaning cartridge for a cassette cleaner for an audio or video player/recorder, as shown and described.

DESCRIPTION

FIG. 1 is a front, top and right side exploded perspective view of a cleaning cartridge for a cassette cleaner for an audio or video player/recorder showing our new design;

FIG. 2 is a front, top and right side perspective view of the cartridge in assembled condition;

FIG. 3 is a top plan view with the outer housing shown as translucent;

FIG. 4 is a front elevational view thereof;

FIG. 5 is a left side elevational view thereof;

FIG. 6 is a right side elevational view thereof; and

FIG. 7 is a rear elevational view thereof.
